(57) **CLAIM**

The ornamental design for a snow brush, as shown and described.

DESCRIPTION

FIG. 1 is a perspective view of a snow brush showing my present design,

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view.

The tips of the individual strands that make up the bristle tufts are omitted within the bounds of each of the round tufts in FIG. 3 for ease of illustration.
